UNITED STATES PATENT OFFICE.

JOSEPH J. WESLEY, OF NEW YORK, N. Y.

PANEL-BOARD.

No. 839,530.

Specification of Letters Patent.

Patented Dec. 25, 1906.

Application filed January 29, 1906. Serial No. 298,340.

To all whom it may concern:

Be it known that I, JOSEPH J. WESLEY, a citizen of the United States, residing at the city of New York, in the borough of Brooklyn and State of New York, have invented certain new and useful Improvements in Panel-Boards, of which the following is a full, clear, and exact description.

My invention relates to panel-boards, and has for its principal object the provision of a panel-board which shall secure all the important and valuable features of the usual panel-board having potential and neutral bus-bars, but which is arranged to occupy a reduced or 15 compact compass, so as to take up a less amount of wall-space.

A further object of the invention is to provide a practical construction of the various metallic parts and fixtures which shall be 20 efficient and easy to manufacture.

With these and other objects in view my invention consists in the construction, combination, location, and arrangement of parts hereinafter set forth and shown, and finally 25 particularly pointed out in the appended claims.

In the drawings, Figure 1 is a top or plan view of a panel-board embodying the principles of my invention. Fig. 2 is a vertical sectional view of the same on the line II II of 30 Fig. 1, and Fig. 3 is a section on the line III III of Fig. 1.

It will be understood that in handling currents in power-stations and in buildings it 35 is customary to distribute the current from the main line by means of panel-boards from which the various branch circuits are completed as required. The most essential points about a panel-board are that it should 40 be simple and free from connections or parts liable to short-circuit the bars and, further, that it should be capable of making good metallic connections with the branch circuits when these are switched into action. 45 In carrying out my present invention I aim to secure these features in addition to a very compact disposition of the parts upon their supporting-base.

Referring to the drawings, in which like 50 parts are designated by the same reference-sign, 1 indicates the supporting-base, of marble or other insulating material, which may be supported upon the usual wooden uprights 2. 3 denotes what I shall term a "supplementary support" and comprises a plate or tablet of marble or other insulating mate-

rial supported from the main base 1 and in parallel and spaced relation therefrom by any suitable means, as by bolts 4 and distance-blocks 5.

The bus-bars are indicated at 6, 7, and 8, respectively, of which 6 and 8 are the potential bars, while 7 is the neutral bar. The usual potentials employed are plus 110, zero, and minus 110 volts. The bus-bars 6, 7, and 8 are each held to the supplemental support 3 by bolts 9 and 10 and the bolts 4, above mentioned. The bolts 9 and 10 also serve an additional purpose as conductors, as will be later described.

Referring to Fig. 1, it will be seen that a number of metallic cross-strips 11 are included beneath the neutral bus-bar 7, being preferably secured in such relation by the bolts 4, which also pass through these metallic cross-strips. The outer ends of the metallic cross-strips 11 are clamped into contact with metallic fixtures 12, which form one part of the switch elements. 13 designates bolts for holding the cross-strips 11 80 against the fixtures 12, said bolts extending into holes in the marble, the lower part of which is counterbored, as shown at 14 in Fig. 2. The purpose of having the bolts in counterbored holes is to preclude any possibility 85 of the fixtures 12 becoming short-circuited on the bus-bars 6 and 8 directly beneath them, but on the other side of the supplemental support 3.

15 and 16 designate additional switch fixtures or elements which are respectively connected to the bus-bars 6 and 8 by the screws 9 and 10 above mentioned, which thereby serve the treble purpose of holding the bus-bars in place, holding the fixtures 15 and 16 95 in place, and establishing a metallic connection between the two.

The movable switch elements are designated at 17 in the drawings and comprise double knife-blade switch-arms journaled 100 upon the terminal bars 18 and 19 of the several branch circuits. 20 designates the usual fuses in each terminal of such circuits.

For the purpose of securing a better contact between the various fixtures 12 and 15 105 and the switch-arms 17 I form the latter in a special way, as indicated in the figures, having a metallic tab or lug 21, which is folded over, so as to make a U-shaped engaging clip in connection with the switch-arm, as 110 clearly shown in Fig. 1. This U-clip is somewhat springy and serves to embrace the

opposed metallic edge of the various fixtures 12, 15, and 16. 22 designates the usual insulating-handles, each connected to a pair of the switch-arms 17, whereby any desired circuits 18 19 may be completed by moving the handles 22 so that the switch-arms are engaged with a pair of the fixtures 12 15 or 12 16, as the case may be.

It will be seen that this construction provides a very compact panel-board arrangement and one in which all the parts are efficiently protected against short-circuiting and which are capable of making good metallic connections with the various branch circuits. Each switch-handle 22 completes one of the branch circuits by connecting its two terminals with one of the potential bars and the neutral bar, respectively, the upper row of branch circuits being applied, for example, to the positive and neutral bar, while the lower row of branch circuits is connected to the negative and neutral bus-bars.

What I claim is—

1. A panel-board comprising a main base or support, a supplemental support held in spaced relation therefrom, potential and neutral bus-bars on opposite sides of said supplemental support, fixtures connected to said bus-bars, and switch-arms for completing various branch circuits with said fixtures.
2. In a panel-board, a supplemental support having a pair of potential bus-bars on its lower side and a neutral bar on the front or face thereof, and connections by which said bars are placed in closed circuit relation with any desired branch circuits.
3. In a panel-board, a supplemental sup-

port having a pair of potential bars on its lower face and a neutral bar on its upper face, fixtures on the upper face of said support, and bolts for holding said fixtures and said potential bars in place and establishing electric contact between them.

4. In a panel-board, a supplemental support having potential bars on its lower face, metallic fixtures upon the upper face and connected to said potential bars, and switch-arms having U-shaped clips or tabs arranged to make contact with said fixtures.

5. In a panel-board, a main base or support, a supplemental support, bus-bars on the lower face thereof, a bus-bar on the upper face, fixtures connected to said first-named bars, and additional fixtures electrically connected to said bar on the upper face.

6. In a panel-board, a supplemental support having potential bars on its lower face, a neutral bar on its upper face, cross-strips connected to said neutral bar, and fixtures upon said front face, said fixtures being in pairs respectively bolted to said potential bars and to said cross-strips.

7. In a panel-board, a main base or support, a supplemental support having potential bars on its lower face, metallic fixtures upon the upper face and connected to said potential bars, and switch-arms for completing various branch circuits with said fixtures.

In witness whereof I subscribe my signature in the presence of two witnesses.

JOSEPH J. WESLEY.
